UNITED STATES PATENT OFFICE.

ZACHARY T. FRENCH, OF BOSTON, MASSACHUSETTS.

SEWING-MACHINE.

SPECIFICATION forming part of Letters Patent No. 558,679, dated April 21, 1896.

Application filed May 14, 1894. Serial No. 511,076. (No model.)

To all whom it may concern:

Be it known that I, ZACHARY T. FRENCH, of Boston, county of Suffolk, State of Massachusetts, have invented an Improvement in 5 Sewing-Machines, of which the following description, in connection with the accompanying drawings, is a specification, like letters and figures on the drawings representing like parts.

10 This invention is intended as an improvement on the class of machine shown in United States Patent No. 427,068, dated May 6, 1890, and has for its object to provide means for keeping the looper heated properly by the use 15 of steam or other hot fluid as the heating medium.

In accordance with this invention I have combined with the head of the machine a steam-box which embraces the rock-shaft carrying the looper, said steam-box having pipes 20 to conduct steam into and from the box.

Figure 1, in side elevation, represents a sufficient portion of the sewing-machine referred to with my improvements added to enable 25 my invention to be understood. Fig. 2 is an enlarged top or plan view, partially broken out, of the steam-box; and Fig. 3 is a partial front end view of said machine.

Referring to the drawings, A² represents 30 the framework; A³, the head of the machine, in which slides the awl-bar a. b is a guard or fender to act against the inner sole. b² is presser-foot or channel-gage. m is a hook-gage to engage the edge of the inner sole. c² is a rocking lever carrying the presser-foot b². i is a rocking lever carrying the work support or plate h. b¹⁴ is a lever having a rocking lever which in practice will actuate the bar carrying the hooked needle. These 35 devices are and may be substantially as in United States Patent No. 427,068, referred to, wherein like letters are used to designate like parts. The thread-guide f, connected to the vertical rod f', provided at its upper end with 40 a crank and connected to a reciprocating rod f², is also the same as represented in the said patent.

In accordance with this invention, however, 45 wherein means have been provided for keeping the rod and thread-guide hot, I have devised the instrumentalities which I will now describe.

I have connected to the head of the machine by a suitable screw a steam-box 21, said steam-box having a lug 22, through which said screw 55 is extended. The steam-box has a steam-inlet 23, which receives the pipe 24, said pipe being in communication with some suitable reservoir or supply for steam or other hot liquid. The said box has an outlet 27, which 60 has connected to it a pipe 28, provided with a coil 28^X intermediate its length, said pipe being led into one end of a stationary shaft 25, which forms the fulcrum for the rocker-lever i, said shaft being hollow and having 65 connected to it at its opposite end a pipe 26, which is preferably led back to the source or supply for steam or other hot fluid, or said pipe may be an exhaust-pipe.

It will be obvious that the flow of the steam 70 or other hot fluid might be in exactly the opposite direction through the steam-box and yet produce substantially equally beneficial results.

The steam-box 21 is so shaped as to embrace the rod f', carrying the thread-guide, 75 said steam-box, by contact with the said rod, keeping it and the thread-guide hot and obviating the use of a gas-flame, such as has commonly been employed in connection with 80 the machine referred to.

The steam-box attachment is properly placed substantially as shown in Fig. 1, then adjusted slightly up or down to the precise position desired, the coil 28^X permitting sufficient spring for this adjustment, and is then clamped in fixed position by means of the set-screw 20. The coil 28^X in the pipe 28 gives 85 a degree of flexibility to the latter, so that in case the parts do not exactly aline as they 90 should the pipe 28 will readily spring or give sufficiently for accurate adjustment. This coil also serves to take up the vibrations of the head and prevent the breaking away of the steam-box in case it should be secured to 95 the head by soldering.

Having described my invention, what I claim as new, and desire to secure by Letters Patent, is—

1. In a wax-thread sewing-machine, a work-support, the arm for carrying it, and the hollow rod forming the fulcrum for said arm; and a thread-guide, a rocking rod to which it is attached, combined with an independent steam-

box attached to the head of the machine, and embracing said rocking rod, and pipes directly connecting said steam-box with the said hollow rod, to operate, substantially as described.

5 2. In a wax-thread sewing-machine, a work-support and its carrying-arm, the latter being provided with a hollow fulcrum, a thread-guide, and a rocking rod to which said thread-guide is attached, combined with an adjustable steam-box secured to the head of the machine, and embracing said rocking rod, and a steam-pipe directly connecting said steam-

box with said hollow fulcrum, the said steam-pipe having a coil formed therein intermediate its length to permit the same to yield 15 slightly, substantially as described.

In testimony whereof I have signed my name to this specification in the presence of two subscribing witnesses.

ZACHARY T. FRENCH.
